APPARATUS FOR VACUUM CRYSTALLIZATION

Martin J. Kerner, Buffalo, N. Y., assignor to
 Buffalo Foundry & Machine Company, Buffalo, N. Y., a corporation of New York

Application July 29, 1932, Serial No. 626,179

3 Claims. (Cl. 159—45)

This invention relates to an improved method of vacuum crystallization and apparatus therefor.

In crystallizing apparatus as heretofore constructed each of the several effects of the apparatus was equipped with its own condenser and steam ejector or pump which were wholly independent of the corresponding equipment of the other effects which is objectionable on account of the large quantities of cooling water required to operate under the necessarily high vacuums. In many such installations the cooling water is above the temperature of the vapor of the last stage and in such cases it was necessary and it has been a common practice to compress this vapor to a higher pressure so as to make it possible to use the available water for condensing purposes. Owing to the last stage being normally under an extremely high vacuum the compression of this vapor had to be done in a number of stages which involved the use of additional apparatus and also consumed an undue amount of steam.

One of the objects of this invention is to reduce to a minimum the amount of steam and water used in creating the vacuums in the various stages of the operation of the apparatus.

Another object of this invention is to more efficiently separate the salts that are crystallized during these stages from the mother liquor so that when the liquor is returned to the apparatus for further cooling, it remains in touch with the colder liquor and thus gives the crystals a better opportunity to grow.

A further object of this invention is to so organize the apparatus that in its method of operation it is possible to continuously draw liquor and vapors from one stage to another without interrupting the operation of the apparatus.

In the accompanying drawings:

40 Figure 1 is a diagrammatic representation of one form of apparatus embodying my invention and carrying out my improved method of crystallization under vacuum.

45 Figure 2 is a similar view of a modified form of an apparatus constructed in accordance with my improvement.

Figure 3 is another view of the same character showing a further variation of this invention.

50 In the following description similar characters of reference indicate like parts in the several views of the drawings.

Referring to Fig. 1, the numerals A, B, C represent a plurality of crystal or salt precipitators forming part of the first, second and third units, 55 respectively, of the means forming the successive

effects or stages in the operation of this improved method of producing crystallization of the salt in the mother liquor.

In general these precipitators have precipitating chambers 10, 11, 12 respectively, each of which is formed with a hollow body provided with an upright cylindrical sidewall 13, a downwardly tapering conical bottom 14, and an upwardly dished top 15. The bottom is provided at its lower end with a crystal outlet 16 which is controlled 10 by a valve 17, and above the top is arranged a liquid outlet dome 18 which communicates at its lower end with the upper end of the respective precipitating chamber and is provided on its opposite sides with two liquid outlets 19, 20 the 15 former for use in re-circulating some of the liquid in the same unit and the latter for transferring some of the liquid from the respective unit to another unit.

Above the several precipitators is arranged a 20 series of separators D, E, F associated, respectively, with the first, second and third effects, for separating the liquid and vapors which are discharged into the precipitators preparatory to taking out the crystals or salts from the liquid and condensing some of the vapors and utilizing the heat in the uncondensable vapors for heating purposes in another unit. One of these separators forms an element in the unit of each effect and each separator comprises a separating chamber formed within a hollow body having an upright cylindrical side wall 21, a downwardly tapering conical bottom 22, an upwardly dished top 23, a liquid inlet 24 in its side, a liquid outlet pipe 25 extending from the lower end of its bottom downwardly through the dome of the respective precipitator and terminating at its lower end in the central part of the precipitating chamber, and a vapor outlet 26 arranged at the upper 25 end of the separating chamber. Circulation of some of the crystal laden liquor within the same unit is effected by a unit return pump 27 having its inlet connected by a pipe 28 with the outlet 19 of the companion dome 18 while the outlet of this pump is connected with the liquor inlet 24 of the companion separating chamber by a pipe 29. 30

Each of the separators is provided between the upper and lower ends of the body forming its chamber with an inlet 30 for the salt solution, 50 and in the unit of the first effect this inlet is connected with a supply pipe 31 whereby the original mother liquor is supplied to the apparatus, and in the second and third effects the inlet 30 in each instance is connected by a transfer pipe 32 with 55

the transfer outlet 20 of the dome of preceding effect. The original supply pipe 31 and the transfer pipes 32 are each provided with a valve 33 for controlling the flow of mother liquor through the same.

Each of the separators is provided on its inner side with a depending deflector 34 which directs the vapors and liquid issuing from the respective circulating pipe 28 downwardly toward the bottom of the respective separating chamber. Within the separating chamber between the deflector 34 and the vapor outlet 26 of this chamber is arranged a baffle device for eliminating from the vapors any liquid entrained therein which device in its preferred form comprises a plurality of inclined baffle plates 35 which are arranged in a vertical series and extend alternately inwardly from opposite sides of the wall of the separating chamber so that the vapor in passing from the lower edge of the deflector 34 to the vapor outlet 26 will be compelled to take a tortuous path and thus cause liquid entrained in the vapor to be deposited on the underside of the baffle plates and flow from the latter to the lower part of the separating chamber where it joins the unvaporized liquid and is delivered with the same into the precipitator arranged underneath.

The operation of the precipitator and separator in the unit of each effect is as follows:—

It will be assumed that the mother liquor is delivered in a heated condition into each separator through the inlets 30, that the pumps 27 are running and that an exhausting device serves to create a vacuum in each unit so as to withdraw the vapors through the vapor outlets 26 of the several separating chambers. Under these conditions the crystal laden liquor or salt solution will pass from the lower end of each separating chamber through the respective delivery pipe 40 into the precipitating chamber below. As the crystal laden liquor enters the precipitating chamber part of the crystals therein will drop to the bottom of this chamber from where they are removed upon opening the valve 17 while the liquid containing more or less crystals passes from the lower end of the pipe 25 upwardly in the precipitating chamber to the dome thereof. Some of this liquor is withdrawn by the pump 27 from the dome and carried back to the same separating chamber for the purpose of further separating vapors therefrom in the separating chamber and also further eliminating crystals therefrom in the precipitating chamber.

Some of the mother liquor is also withdrawn by vacuum through the transfer pipe 32 and carried over into the separating chamber of the unit in the next following effect. Any vapor separated from the liquor as it enters the separating chamber through the original inlet 30 and the return inlet 24 is carried off by vacuum through the vapor outlet 26 of the separator.

The several effects of this apparatus include means for condensing the condensable vapors which are withdrawn from the separators, also means for creating a vacuum in the apparatus and causing the vapors to be carried away from the separators to the condensers. The condensers for the units of the first, second and third effects are designated G, H, I and each of these condensers comprises a condensing chamber formed within a hollow body having an upright side wall 36, a downwardly tapering conical bottom 37, an upwardly dished top 38, a water inlet 39 near its top, a water outlet 40 at its bottom, a vapor outlet 41 at its top, a vapor inlet 42 near

its bottom, and a plurality of catch basins 43 arranged in staggered relation within the condensing chamber. Water is supplied to the uppermost basin of the condenser of the unit constituting the third effect by a pipe 44 containing a controlling valve 45, and from this uppermost basin the water flows in the form of cascades successively to each lower basin and finally escapes through the water outlet 40 at the bottom of the condensing chamber. From each condensing chamber of the third and second effects the water is carried by a transfer pipe 46 to water inlet 39 of the next preceding condensing chamber and each of these transfer pipes is provided with a depressed trap 47, the water in which forms a seal to prevent any one of these condensing chambers venting into the other.

The water outlet 40 of the condenser of the first effect connects with the upper end of a discharge pipe 48 which has its lower end immersed in water contained in a trap tank 49, thereby forming with the condensing chamber of the first effect a barometric condenser which creates a vacuum in the chambers connected with the upper end of the pipe 48 due to a falling column of water therein, which water may be discharged from the tank 49 into a sewer or elsewhere as desired.

The vapor is conducted from the vapor outlet 26 of the separating chamber of the third effect 30 C to the vapor inlet 39 of the condensing chamber of the third effect by a vapor transfer pipe 50 containing a comparatively large steam operated ejector 51 whereby the vapor is forcibly carried away from this separator and a vacuum is created 35 in the latter and other parts of the apparatus communicating therewith.

The vapor outlet 26 at the upper end of the separating chamber E of the second effect is connected by a vapor transfer pipe 52 with the vapor inlet 42 of the companion condensing chamber H and the separating chamber D of the first effect has its vapor outlet 26 also connected by a pipe 53 with the vapor inlet 42 of the companion condensing chamber.

Means are provided for withdrawing non-condensable vapors from the upper end of each condensing chamber to thereby create a vacuum therein. This is preferably effected by connecting a comparatively small steam actuated ejector 54 with the vapor outlet 41 of each condensing chamber. The outlet of the ejector 54 of the third effect is connected by a vapor pipe 55 with the vapor transfer pipe 52 leading from the separating chamber E to the condensing chamber H of the second effect, the outlet of the vapor ejector 54 of the second effect is connected by a pipe 56 with the pipe 53 leading from the separating chamber D to the condensing chamber G of the first effect, and the outlet of the vapor ejector 54 of the condensing chamber G of the first effect leads by a pipe 57 to the atmosphere.

As the vapors pass from the vapor inlet 42 to the vapor outlet 41 thereof the same pass through the cascades of water and more or less of the condensable vapors therein are liquefied and the resulting condensate mixes with the condensing water from the pipe 44 and flows to the inlet 39 of the condensing chamber of the second effect. In the condensing chamber of the second effect the vapors from the separating chamber E of the second effect discharged by the pipe 52 and the vapors carried from the condensing chamber of the third effect by the pipe 55 are passed through 75

the streams of water in the condensing chamber of the second effect, thereby causing further liquefaction of the condensable gases or vapors, which condensate joins the water passing from the condensing chamber of the second effect to the condensing chamber of the first effect.

The vapors withdrawn from the condensing chamber H of the second effect and the vapors discharged from the separating chamber of the first effect are carried by the pipes 56, 53 to the lower end of the condensing chamber of the first effect, and thence pass upwardly through the sprays or streams of water therein, whereby any of the vapors which are condensable will be liquefied and descend with the water into the pipe 48 and pass on the sewer.

Any uncondensable vapors which pass through the streams of the water in the condensing chamber G are merely ejected through the pipe 57 as waste. The mother liquor leaving through the outlet 20 of the dome of the third stage at its lowest temperature can be further treated either by evaporation or other means or returned to the system for further precipitation, for which purpose the liquor may be withdrawn from said outlet 20 by a pump 58 connected therewith by a pipe 59.

The operation of the apparatus as a whole is as follows:—

30 Live steam is supplied to the main ejector 51 at the rate of 950 pounds per hour, and to each of the auxiliary ejectors 54 at the rate of 70 pounds per hour equivalent to 125 pounds gage pressure. The mother liquor is supplied by the supply pipe 31 at a temperature of 210° F., and this temperature drops successively to 161° F., 105° F. and 59° F. as the mother liquor in turn enters the separators of the first, second and third effects. The steam supplied to the ejector 51 withdraws the vapors from the separator F at the rate of 650 pounds per hour producing a vacuum of 29½ inches of vacuum in this separator with the barometer at 30 inches, and this vapor added to the 950 pounds of steam supplied to the ejector 51 makes a total of 1600 pounds of vapor entering the condenser I of the third effect.

In this condenser a temperature of 101° F. and a vacuum of 28 inches is maintained by the supply of water at normal temperature of approximately 75° F. and 157 gallons per hour and the supply of steam to the ejector 54 of the third condenser at the rate of 70 pounds per hour. The condensation of the steam supplied to the ejector 51 added to the water supplied by the pipe 44 produces a total of approximately 160 gallons per minute which is delivered to the condenser H of the second effect at a temperature of 96° F., which volume of water is finally discharged from the sump or tank 49 of the barometric condenser of the first effect.

60 In the condenser H and the separator E of the second effect a vacuum of 27 inches is produced by the ejector 54 connected with the condenser H of the second effect, and vapor is withdrawn by this ejector from this unit at the rate of approximately 670 pounds per hour. The non-condensable vapors withdrawn by the ejector 54 from the condenser I of the third effect are compressed to a pressure equivalent to that maintained in the condenser H, the mixed vapors being conducted from the ejector 54 of condenser I by a pipe 55 to the condenser H.

The steam supplied to the ejector 54 of the first effect produces a vacuum of 20 inches in the condenser G and the separator D of this effect and

results in the production of 720 pounds of vapor per hour in this unit, during which operation the uncondensable gases or vapors which are withdrawn from the condenser H of the second effect to the condenser I of the third effect are conducted by the pipe 56 to the separator and condenser of the first effect.

The sum of the non-condensable gases is finally discharged through the pipe 57 to the atmosphere, and the final mother liquor is discharged through the outlet 20 of the dome 18 of the third effect.

As the cooling water passes through the condenser I the same has been raised in temperature from 75° F. to approximately 96° F. and has also 15 been raised in quantity from 157 g. p. m. to 160 g. p. m. due to the addition thereto of condensation of vapors in the condenser I.

As the cooling water flows from the condenser H of the second effect to the condenser G of the first effect its temperature has been raised to 105° F., and when the condensate escapes from the pipe 48 of the condenser G of the first effect its temperature has been raised to approximately 115° F.

During the operation of the apparatus shown in Fig. 1, as described the temperatures of the liquid in the precipitators F, E, and D are approximately 75° F., 125° F. and 173° F., respectively, while the temperature of the vapors in these precipitators is approximately 59° F., 105° F. and 161° F., respectively.

In this apparatus a comparatively large amount of steam is initially used for compressing the vapors withdrawn from the separator F and delivered to the condenser I of the third effect and only comparatively small amounts of steam are required for removing the non-condensable gases from the condensers of each effect and delivering the same to the condenser of the preceding effect for raising the temperature of the vapors in the latter. A very considerable economy in the use of steam and water is thus effected for extracting the crystallizable salts in a certain quantity of mother liquor compared with the methods and apparatus heretofore known or used.

The construction and operation of the modified form of the apparatus shown in Fig. 2 is as follows:—

In this apparatus three effects or stages are employed in which the precipitators A, B, C, the separators D, E, F and the liquor transferring and re-circulating means are substantially like those shown in Fig. 1 and the description and reference characters hereinbefore employed in connection with Fig. 1 therefore also apply to the corresponding parts shown in Fig. 2. In Fig. 2 the transfer pipes 32 containing the valves 33 connect the domes 18 of the first and second effect with the tops of the precipitating chambers 10 of the second and third effects, respectively.

In this modified form of the apparatus comparatively large steam actuated ejectors 60, 61 are connected respectively with the upper ends of the separating chambers E, F of the second and third effects and a single barometric condenser J is employed for disposing of the condensate of the several units and assisting in the formation of a vacuum in the separating chambers of the several effects. The ejector 61 receives steam through a pipe 62 for withdrawing vapor from the upper end of the separator F of the third effect and discharges the same through a pipe 63 into the upper end of the

separator E of the second effect. The ejector 60 is operated by steam supplied by a pipe 64 for withdrawing vapor from the upper end of the separator E of the second effect and discharges 5 the same by a pipe 65 into a coupling 66 which communicates with the upper end of the separator D of the first effect. The pipe 65 and coupling 66 are connected by a pipe 67 with the lower part of the body J of the condenser, which 10 latter is constructed like the condenser G of the first effect in Fig. 1, and is provided adjacent to its upper end with a water supply pipe 68 having a controlling valve 69 while its top connects with a comparatively small ejector 70 supplied with steam by a pipe 71 and its bottom 15 is connected with a barometric discharge or stand pipe 72 leading to a trap tank 73 similar to the tank 49 in Fig. 1.

In this organization the vapors from the separator F in the third stage are removed from the 20 ejector 61 and discharged into the upper part of the separator E of the second stage. The vapors formed in the separator E of the second stage plus the vapors from the separator F of the third 25 stage are now withdrawn by the ejector 60 and in turn discharged into the condenser J together with the vapors drawn from the condenser D of the first stage, the exhausting effect on the vapors in the last-mentioned condenser being produced 30 by the action of the barometric condenser J. All of the uncondensable gases in the vapors in this apparatus are drawn off from the top of the condenser body J and discharged to the atmosphere.

35 Assuming that the fresh mother liquor is supplied through the pipe 31 at a temperature of 210° F., condensing water through the pipe 68 at a temperature of 75° F. and that steam is supplied to the several ejectors 60, 61 and 70 at 125 pounds 40 gage pressure, the temperature of the solutions in the separators F, E, D of the third, second and first stages will be approximately 75° F., 125° F. and 175° F. respectively; the temperature of the liquid in the stand pipe 72 will be about 150° F.; 45 the temperature of the vapors in the separators F, E, D of the third, second and first stages will be about 59° F., 109° F. and 159° F. respectively, and the vacuum in the separators F, E, D of the third, second and first stages will be approximately 50 29.5 inches, 27.5 inches and 20 inches respectively.

The further modified form of apparatus containing this invention and shown in Fig. 3 is constructed as follows:—

55 In this construction the precipitators A, B, C and the separators D, E, F of the first, second and third stages or effects are also similar to those shown in Fig. 1 and the previous description of the construction and operation of the 60 same parts therefore applies to both. An important difference between the forms shown in Figs. 1 and 3 is that in Fig. 3 only the separator F of the third effect is provided with an ejector 74 which is actuated by steam from a pipe 75 and the 65 body K of a barometric condenser is connected by pipes 76, 77 and a coupling 78 with the outlet of the ejector 74 and the vapor outlet at the top of the separator D, and an individual condenser is provided for the second stage, the body L of 70 which is connected with the vapor outlet at the top of the separator E by an outlet pipe 79. The condenser bodies K, L are provided with individual water supply pipes 80, 81 for condensing purposes, also with water discharge pipes 82, 83 75 leading to the trap tanks 84, 85, and also with

individual steam actuated ejectors 87, 86 for withdrawing the uncondensable gases from the condensers K, L and discharging the same to the atmosphere.

In Fig. 3 the mother liquor is conducted directly by the pipe 31 into precipitating chamber 10 of the first effect, and this liquid is transferred by the pipes 32 containing the valves 33 from the domes 18 of the precipitators of the first and second effect to the precipitating chambers 10 10 of the second and third effects, respectively.

Assuming that water at a temperature of 75° F. is supplied through the pipes 80, 81 to the condensers, that steam at 125 pounds gage pressure is supplied to the ejectors 74, 86 and 87 and that 15 the mother liquor is supplied through the pipe 31 at a temperature of 210° F., this will result in a temperature of 59° F., a vacuum of 29.5 inches and formation of 650 pounds of vapor per hour in separator F of the third stage, a temperature of 109° F., a vacuum of 27.5 inches and the formation of 670 pounds vapor per hour in the separator E of the second stage, and a temperature of 159° F., a vacuum of 20 inches and the formation of 710 pounds of vapor per hour 25 in the separator D of the first effect, while the temperature of the condensate escaping from the condensers K, L will be respectively 150° F. and 100° F.

A feature common to all the several forms of 30 this invention is that non-condensable gases are removed from the separator body of one stage and blown into the separator body of a preceding stage for the purpose of using as little steam as possible for ejecting or compressing the vapors. 35

The construction in Fig. 2 further differs from that shown in Fig. 1 in that the latter employs individual condensers G, H, I for the vapors in the several stages, while in the former the vapors are carried from the separators D, E, F of the 40 several stages to a single condenser J.

The construction shown in Fig. 3 further differs from that shown in Fig. 1 in that the former employs one condenser K which is common to the separators D, F of the first and third stages, 45 and an individual condenser L is employed for use with the separator E of the second stage.

In addition to effecting a considerable saving in heat and water, this apparatus produces a circulation of the liquor through the apparatus so 50 as to cause a uniform cooling of the entire mass of solution which is subjected to the process of crystallization.

I claim as my invention:—

1. An apparatus for crystallizing salts in a solution, comprising a plurality of effects each of 55 which includes a separating chamber in which vapors are separated from the mother liquor and which has a downwardly projecting outlet, a wide settling chamber into which said outlet projects 60 and in which salt crystals are separated from the mother liquor, and a narrow outlet chamber which receives mother liquor from the central upper part of the settling chamber, liquor conduits each connecting the narrow outlet chamber of each 65 preceding effect with the separating chamber of the next following effect, a condensing means associated with each of the separating chambers, means for supplying cooling water to each of said condensing means, steam operated ejecting means 70 for withdrawing vapors from the separating chamber of the last effect and discharging the same to the condensing means of the same effect, and steam operated ejecting means for withdrawing vapors from the condensing means of 75

each succeeding effect and discharging the same successively to the several condensing means of the preceding effects and to the atmosphere.

2. An apparatus for crystallizing salts in a solution comprising a plurality of effects each of which includes a separating chamber in which vapors are separated from the mother liquor, and which has a downwardly projecting outlet, a wide settling chamber into which said outlet projects and in which salt crystals are separated from the liquor, a narrow outlet chamber which receives liquor from the central upper part of the settling chamber, a liquor conduit connecting the narrow outlet chamber of each preceding effect with the separating chamber of the next succeeding effect, a condensing chamber associated with each of said vapor separating chambers, means for supplying condensing water successively to the condensing chambers of the several effects including a water conduit connecting the lower part of the condensing chamber of each succeeding effect with the upper part of the condensing chamber of the respective preceding effect and containing a water seal which prevents the passage of vapor through the same from one of these condensing chambers to the other, a steam operated ejector having its inlet connected with the upper part of the separating chamber of the last effect and its outlet connected with the condensing chamber of the respective effect, a steam operated ejector having its inlet connected with the condensing chamber of the last effect and its outlet connected with the condensing chamber of the next preceding effect, a steam operated ejector having its inlet connected with the condensing chamber of the first effect and its outlet leading to the atmosphere, and a vapor conduit connecting the upper part of each preceding separating chamber with the lower part of the condensing chamber of the corresponding effect.

3. An apparatus for crystallizing salts in a solution comprising a plurality of effects each of which includes a separating chamber in which vapors are separated from the mother liquor and which has a downwardly projecting outlet, a wide settling chamber into which said outlet projects and in which salt crystals are separated from the liquor, a narrow outlet chamber which receives liquor from the central upper part of the settling chamber, a pump which withdraws liquor from said narrow outlet chamber and discharges the same into the respective separating chamber, a liquor conduit connecting the narrow outlet chamber of each preceding effect with the separating chamber of the next succeeding effect, a condensing chamber associated with each of said vapor separating chambers, means for supplying condensing water successively to the condensing chambers of the several effects including a water conduit connecting the lower part of the condensing chamber of each succeeding effect with the upper part of the condensing chamber of the respective preceding effect and containing a water seal which prevents the passage of vapor through the same from one of these condensing chambers to the other, a steam operated ejector having its inlet connected with the upper part of the separating chamber of the last effect and its outlet connected with the condensing chamber of the respective effect, a steam operated ejector having its inlet connected with the condensing chamber of the last effect and its outlet connected with the condensing chamber of the next preceding effect, a steam operated ejector having its inlet connected with the condensing chamber of the first effect and its outlet leading to the atmosphere, and a vapor conduit connecting the upper part of each preceding separating chamber with the lower part of the condensing chamber of the corresponding effect.

MARTIN J. KERMER.
